UNITED STATES PATENT OFFICE.

FRED H. HARDMAN, OF TAUNTON, MASSACHUSETTS.

WIRE-NAIL MACHINE.

SPECIFICATION forming part of Letters Patent No. 317,130, dated May 5, 1885.

Application filed December 1, 1884. (No model.)

To all whom it may concern:

Be it known that I, FRED H. HARDMAN, of Taunton, in the county of Bristol and State of Massachusetts, have invented certain new and useful Improvements in Wire-Nail Machines, of which the following is a full and clear specification.

The object of my invention is to provide an improved machine for forming nails from a continuous length of wire in a more rapid and uniform manner than heretofore.

The invention consists in the construction, combination, and arrangement of the mechanism hereinafter more fully described, and set forth in the claims, whereby wire nails of any desired size and length may be produced having heads of any desired size, and of various sizes, formed from wire of uniform size or of various sizes, as hereinafter set forth.

Figure 1 represents a top plan of a wire-nail machine constructed according to my invention. Fig. 2 represents a vertical longitudinal central section of the same. Fig. 3 represents a side elevation of the same. Fig. 4 represents a perspective view of a detached portion. Fig. 5 represents a similar view of another portion. Fig. 6 represents a section view of a portion of the cam mechanism.

A represents the supporting frame or bed of the machine, upon which the several operating devices are mounted, as shown.

B B' represent the dies which grasp the nail-wire while it is being headed.

The lower die, B, is secured to the rigid cross bar or frame C, which is cast with the said bed A of the machine, forming a part thereof. The said die B is circular, and is held in position by the axial bolt E, passing through the center of the same within a hole provided to receive it, and through the said cross-frame C, and provided with a screw-thread and nut, whereby the said die may be partially turned or rotated upon said bolt E, so as to permit various portions of its periphery to be turned to the top or into operative position to grasp the nail-wire at a new or fresh point without removing the die. The said retaining-bolt E passes through the said cross-frame C within an oblong or slotted hole,

whereby the said lower gripping-die, B, may be adjusted vertically by means of the set-screw a, which has a bearing against the bottom portion of the said die, as shown, so as to adjust the same to the various sizes of gripping-dies used.

The upper die, B', is secured in like manner to the adjustable or movable cross-lever arm G, one end of which is pivoted to the said cross-frame C, near one side of the said bed-piece A, and extends across the same to the opposite side, and its free end rests upon the spring g, as shown in Fig. 3, the said die B' being secured in position by the bolt E' passing through the center of the same, and through a slightly oblong hole formed through the said pivoted cross-lever arm G, and is adapted to be adjusted vertically by means of the set-screw a', whereby the said gripping-dies B B' may be adjusted to firmly hold the size of nail-wire being used, but cannot be adjusted toward or from the cutting-dies, as hereinafter described.

The wire z, from which the nails are to be formed, is fed forward through the said gripping-dies B B' by means of a feeding device composed of a reciprocating block, b', having an orifice or opening for the passage of the wire and a pivoted lever, c, provided at its shorter end with a vertical dog or chisel, d, pressed by a spring, d', under its opposite longer end, against the wire, said dog or chisel being thus adapted to bite or grasp the wire when the said block is moving toward the said gripping-dies B B', and to slip on the wire when the block is moving in the opposite direction. The upper die, B', rests loosely upon the lower die, B, so that it exerts no pressure on the wire between said dies, excepting when pressed downward by the cam F, secured upon the driving-shaft H. Said cam F acts upon a friction-roll, e, provided at the vibrating end of the long curved lever J, the opposite end of which is pivoted to a projection, I, formed upon the adjustable bed-piece A' of the machine, and provided near the pivoted curved end, upon the under side, with a socket-bearing within which is fitted the upper ball end of the toggle K. The lower end of said

toggle rests in a cavity formed in the upper surface and near the moving end of the said cross-lever arm G, whereby a very powerful grip or great pressure may be brought upon 5 the upper die, B', at each revolution of the said cam F, and when the end of the said curved lever J has been released from the action of the said cam it is forced upward by the spring f, and the end of the pivoted cross-lever arm 10 G is correspondingly forced upward by the spring g, whereby the upper die, B', is caused to rest lightly upon the said nail-wire, or entirely removed therefrom while the said wire is being fed through the dies, as above 15 described.

The said dies B B' are preferably formed on the perimeters of circular disks or blocks of steel, each having a series of half-dies, and secured in the desired positions by the center 20 bolts, as above described.

L represents the header, which upsets the end of the wire after the separation of a nail therefrom, and thus forms the head of the next nail. The header consists of the usual hammer, 25 L, secured within the end of the horizontal slide-bar M, which is adapted to reciprocate in a longitudinal groove or guideway formed in the adjustable bed A', and is reciprocated by means of the cam N, secured upon the driving-shaft H, and which contacts with a projection formed upon the said slide-bar M as it rotates, and thus draws the hammer L and slide-bar M back, compressing the vertical 30 spring-bars Q until the said cam N slips past or from the said projection h, when the force of the said spring Q impels the said bar and hammer forward, so as to cause a sharp or quick blow upon the projecting end of the wire, and thus form the head for the nail as desired.

40 The cutting-dies P P are formed as usual, and secured to the short ends of the pivoted cutting-levers R, as shown in Fig. 5, the opposite longer ends being provided with friction-rolls, and actuated by means of the cams 45 S and T, secured upon the driving-shaft H, one end of which has secured thereon the usual belt-pulleys and balance-wheel, as shown in Fig. 1. The opposite end has secured thereon the crank-wheel U, provided with a dovetail 50 or T-shaped groove extending across its outward face, and provided with an adjustable wrist or crank pin, V, carrying a loose socket or sleeve to which is secured one end of the connecting-rod W, the opposite end of which 55 is connected loosely with the end of the slide-bar Y, the opposite end of which connects with the reciprocating block b' of the wire-feed device, and thus reciprocates the said block b', causing the feed device to feed the wire intermittently. The length of the feed movement 60 may be regulated by adjusting the said wrist-pin V from or toward the center of the said crank-wheel U.

The time of the various operations of the 65 machine is as follows: Suppose a nail to have been severed and the cutting-dies to have sep-

arated, leaving a short end of wire projecting from the gripping-dies. The hammer L and slide-bar M, the rear end of which bears against the powerful spring-bars Q, is released by the 70 said cam N, the spring Q impels the header forward with great force, thus upsetting the projecting end of the wire and forming the head. While the wire is held, the feed-block moves backwardly and takes a new hold on the wire. The header now recedes, cam F partially revolves, with shaft H, and allows springs f and g to raise the levers G J, which releases the upper gripping-die, and then the feed-block moves forward-feeding the wire 75 along between the gripping-dies. Next, cam F revolves so as to press downward the said levers G J, thereby bringing the upper gripping-die down firmly upon the wire. Then the cutting-dies approach the wire and act upon it, 80 forming the point of the nail last headed, and severing it or nearly severing it from the wire. The cutting-dies then separate, and to insure the nail leaving the wire before the header reaches it the clearer i knocks the nail off, if the cutters have failed to remove it, and then the header again advances and upsets the nail-wire, as before. The clearer i is formed or curved as shown in Fig. 4, its rear end being connected to the pivoted rocking cross-frame X, to one end of which is secured the short arm t, the outward end of which is adapted to engage within the notch p, formed in the periphery of the wheel F' on the driving-shaft H, being forced within the 90 said notch by means of the spring r, secured to the bed of the machine, thus tilting the downward-curved end of the clearer against the nail at the proper moment to detach the nail and return to its former position before 95 the header advances to form the next head, as before. It will be understood that the end of the clearer projects over the nail as formed.

The detached nails may be conducted from the machine, or permitted to drop through an 100 aperture in the bed into a receptacle below. Now, in order that the amount of stock in 105 the heads of the nails formed from the same size of wire may be varied, I have provided an adjustable bed-piece, A', on the main bed-piece A, and which may be moved longitudinally thereon by means of collar-screws H', which pass through projections L', formed at one end of the bed-piece A, and enter screw-threaded holes formed in the end of the adjustable bed-piece A', and is then secured in 110 such position by the vertical screw-bolts P', extending through holes slightly oblong or slots formed in the said bed-piece A, and fitting snugly within holes formed through the 115 adjustable bed-piece A', as shown.

It will be seen and understood that all of the operating mechanism, except the cross-lever arm G and gripping-dies B B', is mounted upon the said adjustable bed-piece A', and is moved therewith toward or from the gripping-dies B B', which are permanently fixed 120

upon the said bed-piece A. As the impact of the header against the gripping-dies in heading the nails renders the solidity and rigidity of the same very important, in order that the heads of the nails may be of uniform size, it is found that the slightest variation or movement of the gripping-dies from the cutting-dies after the gripping-dies have been adjusted in relation to the cutting-dies 5 by means of the usual devices employed—such as set-screws—causes a considerable variation in the size of the heads of the nails being formed, as the very rapid and constant blows given by the header loosen the screw-bolts by which the adjustable gripping-dies are secured in position to the cutting-dies upon the bed-piece of the machine, and allow the same 10 to be moved or forced gradually from their position thereon. I am enabled to overcome 15 this objection by constructing the support for the gripping-dies in a continuous piece with the main bed of the machine, which, being cast of iron in one solid piece, insures perfect fixity 20

and rigidity of the same at the desired point upon the bed of the machine, and which the 25 constant jar of the header cannot impair; and, by constructing the cutting-dies and other actuating devices adapted to be adjusted toward or from the gripping-dies, the size of the heads of the nails may be formed of the 30 desired amount of stock, and continued uniformly throughout such size of wire, as may be desired, which is of great importance.

Having thus described my invention, what I claim is—

The combination, with the gripping-dies 35 permanently secured to the bed-piece of the machine, of the adjustable cutting-dies, and mechanism for adjusting the cutting-dies toward and from the gripping-dies, substantially 40 as described.

FRED H. HARDMAN.
